HOLDER FOR STENOGRAPHERS'
NOTEBOOKS

Everett M. Dougherty, Milwaukee, Wis.

Application January 2, 1932. Serial No. 584,367

5 Claims. (Cl. 120—28)

My invention relates to improvements in holders for stenographers' notebooks and other articles of similar character.

The primary object of my invention is to provide an improved holder of easel type which may be employed to support a stenographer's notes in an inclined position when transcribing and which may be instantly readjusted for the taking of additional notes or for the turning of pages. 5 Further objects are to provide means for securely holding the notebook or similar articles to a supporting plate while allowing it to be freely shifted laterally for the purpose of removal when the holder brace is in a folded position; to provide means whereby the book or other article may be automatically clamped in position when the brace is in plate supporting position; to provide such a holder with means for also supporting a pencil in a position to facilitate holding the notebook or preventing the leaves from being 10 displaced by drafts of air; to provide such a pencil holder in association with other means for preventing accidental displacement of the leaves of a notebook, while allowing the leaves to 15 be freely turned or folded backwardly by manual manipulation; to provide means whereby the clamping portion of the holder may be utilized to embrace a backwardly folded cover and associated turned pages in such a manner as to obtain 20 the full benefit of the cylindrical roll produced at the binding by the folded cover and other sheets for preventing displacement of the book during brace folding and holder manipulating operations; and in general to provide simple 25 and inexpensive holders which will have superior adaptability and convenience as compared with holders previously made.

In the drawing:

Figure 1 is an elevation of my improved holder 40 with a portion of the book receiving plate broken away to show the lower portion of the brace.

Figure 2 is a side elevation of the same as seen from the pencil holding margin, with the brace in folded position.

Figure 3 is a fragmentary view of the upper portion of the holder as shown in Figure 2, with a notebook engaged thereby and with the cover and some of the leaves backwardly folded. 45

Figure 4 is a view of the same showing the brace in supporting position.

Figure 5 is an isometric view of the holder as it appears in use when adjusted for holding a notebook in position for transcribing the notes.

Like parts are identified by the same reference 50 characters throughout the several views.

A flat plate 10, preferably formed of metal, is provided with a pair of extensions at its upper margin which are cylindrically rolled to provide bearings 11 for the pivotally supported portions 12 of the brace. 60

The brace is preferably formed of a piece of wire having leg portions 13 at the upper ends of which the wire is inturned as indicated at 14, then bent upwardly as indicated at 15 and outwardly turned to form the hinge pins or pivotal portions 12. At the outer ends of these portions 12 the wire extends beyond the plate 10 and is arcuately curved to form hook shaped portions 16, the extremities of which are connected by a clamping bar 17. The extremities of the hook shaped portions 16 and also the clamping bar 17 are normally supported in sufficient proximity to the upper margin of the plate 10 to allow the backwardly folded portion A of a notebook B to be engaged within the hook shaped portions 16 sufficiently to prevent the book from slipping downwardly along the plate 10 without flattening out the portion A by pressure greater than that exerted by the weight of the book. 75

The major portion of the brace will preferably be formed of a single piece of wire, of which the clamping bar 17 constitutes the middle portion. The lower ends of the legs 13 may be inwardly turned to form foot pieces 18 which constitute a base for the brace. I preferably secure these 80 ends of the wire together by a brace plate 19 having its end margins and bottom margins formed into wire engaging cylindrical clips 20 as clearly shown in Figures 1 and 5.

However, the book may be instantly removed or withdrawn from the holder by pulling it laterally from the plate 10 toward the right hand side of the structure as illustrated in Figure 1. To prevent it from accidentally slipping from the holder in this direction the plate 10 is preferably provided with an upset flange 21 along the lower portion of its right hand side margin so that when the operator desires to remove the book it will first be lifted from the plate 10 along the portion occupied by the flange 21 and withdrawn over the flange. The flange 21 need not project very far 95 forwardly from the surface of the plate 10 inasmuch as its engagement with the back cover of the book would ordinarily prevent an accidental shifting or withdrawal of the book. 100

On the opposite or left hand side of the plate 10 I provide another upset flange 22, the outer margin of which has cylindrically rolled lips 23 forming a fragmentary cylindrical barrel into which a pencil C may be inserted. The lower 110

lip 23' may conform to the surface of a smaller cylinder than those above it, whereby only the point of the pencil may be received within this lip, thus preventing the pencil from slipping 5 downwardly through this hole. When the pencil is in position it cooperates with the lips 23 in holding the associated margin of the exposed sheet of the notebook from being displaced by drafts.

10 In the use of a holder constructed as above described, the front cover and any leaves that are not to be used will first be folded backwardly upon the back cover of the book and the book will then be slipped into place from the right 15 hand side of the holder to engage the backwardly folded portions in the arcuate or hook shaped portions 16, with the unfolded leaves in a position to be engaged by the clamping bar 17. Thereupon the book may be supported in an inclined position by swinging the brace backwardly 20 to the position indicated in Figures 4 and 5, in which position the clamping bar will bear upon the exposed unfolded top leaf of the book and cooperate with the flanges 21 and 22 in securely holding the book in proper position.

25 If additional notes are to be taken, the operator may grasp the holder in a single movement of the hand and fold the brace without any danger of having the book slip out of place. Thereupon the holder may be employed as a rest which 30 may be supported upon the table or upon the knee of the operator while taking notes, the plate 10 being substantially rigid. It will, of course, be understood that when in the position above described for transcribing notes, leaves may be turned backwardly without necessarily folding them between the book and the plate. If desired, the free end of the turned leaf may be pressed 35 between the legs 13 of the brace and thereby retained in the back folded position.

40 It will, of course, be understood that my invention is particularly adapted for use in supporting what may be conveniently termed "end bound" books or tablets as distinguished from those in which the leaves are bound or connected 45 with each other along one side margin.

I claim:

1. A holder for end bound notebooks and similar articles, comprising a substantially rigid 50 plate, in combination with a brace pivotally connected with one end margin thereof, said brace having arcuate arms extending from said pivotal connections beyond the end of the plate, and a clamping bar supported by said arms in prox-

imity to the face of the plate near said end thereof, the brace comprising a piece of wire having portions outwardly turned and serving as pivot pins, and associated portions extending arcuately from the outer ends of the pivot pins to form said bar supporting arms.

2. A holder for end bound notebooks and similar articles comprising a plate having portions of its side margins upset and adapted to receive the material between them, in combination with a brace pivoted to one end of the plate and having a hook shaped arm into which the bound margin of a book may be inserted laterally and held against longitudinal movement along the plate, one of said upset plate margins being provided with inturned arcuate pencil holding lips extending over said plate, whereby a pencil disposed in said lips will be disposed in a position to bear upon the exposed surface of the book.

3. In a holder of the described class, the combination with a work supporting plate having upset side margins and cylindrically rolled extensions at one end near the junction of the respective side margins, and a piece of wire engaged in the cylindrically rolled portions of the 100 plate and having portions bent to form work receiving hooks and clamping extremities adapted, in one position, to hold the work fixedly to the plate, said hooks in another position, being adapted, in co-operation with said upset margins, 105 to hold the work loosely upon the plate, and a hook actuating plate supporting brace.

4. In a holder for end bound notebooks and similar articles, the combination with a brace comprising a single piece of wire bent to form a 110 clamping bar, arcuate hooks at the ends of the bar, and legs extending from the hooks and connected therewith by portions bent inwardly toward each other to provide pivotal portions, of a plate having bearing portions engaged with 115 the pivotal portions on said brace.

5. In a holder for end bound notebooks and similar articles, the combination with a brace comprising a single piece of wire bent to form a clamping bar, arcuate hooks at the ends of the 120 bar, legs extending from the hooks and connected therewith by portions bent inwardly toward each other to provide pivotal portions, foot pieces extending from the ends of the legs toward each other, and a brace plate engaging the legs and 125 foot pieces, of a work supporting plate having bearing portions engaged with the pivotal portions on said brace.
